United States Patent Office

Des. 230,660
Patented Mar. 5, 1974

230,660

PURSE

Jacqueline Hayes, 727 Stewart Ave.,
Daly City, Calif. 94015

Filed Jan. 31, 1972, Ser. No. 222,449

Term of patent 14 years

Int. Cl. D3—01

U.S. Cl. D87—3 F

FIG. 1 is a side elevational view of a purse showing my new design;

FIG. 2 is an end elevational view thereof;

FIG. 3 is an elevational view of the other end;

FIG. 4 is a top plan view;

FIG. 5 is a bottom plan view; and

FIG. 6 is a plan view of the side opposite that shown in FIG. 1.

I claim:

The ornamental design for a purse, as shown.
